UNITED STATES PATENT OFFICE.

AUGUST BOYER, OF EVERETT, WASHINGTON, ASSIGNOR TO SUMNER IRON WORKS, OF EVERETT, WASHINGTON, A CORPORATION OF WASHINGTON.

EDGER-GUIDE.

1,107,751.

Specification of Letters Patent. Patented Aug. 18, 1914.

Application filed December 22, 1913. Serial No. 808,065.

To all whom it may concern:

Be it known that I, AUGUST BOYER, a citizen of the United States, residing at Everett, in the county of Snohomish, State of Washington, have invented a new and useful Improvement in Edger-Guides, of which the following is a specification.

My invention relates to an improvement in edger guides, and more particularly to the construction of the shifter frames and the means employed for mounting the shifter frames for movement transversely of the edger.

The object of my invention is to provide a construction which will more firmly support the shifter frames in position and one which will also reduce the resistance to their moving to the minimum.

My invention comprises the features of construction and the combination of elements which will be hereinafter described and particularly pointed out in the claims.

In the accompanying drawings I have shown my invention in the form which is now preferred by me.

Figure 1 shows one shifter frame in side elevation, the bearing rails and other parts of the machine being shown in section. Fig. 2 is a top plan view of one of the shifter frames detached from the other mechanisms. Fig. 3 is an elevation from the rear showing three shifter frames mounted upon the guide rail, one web of the guide rail being in section.

My present invention is an improvement on the construction shown in Patent No. 991,730 granted May 9, 1911, to the Sumner Iron Works of Everett, Washington, as assignee of Paul F. Lueth and Isaac L. Skeith, and the general form of the edger is similar to that shown in said patent. I have, therefore, not deemed it necessary to show the construction of the edger as fully as it was indicated in said patent.

Extending transversely of the edger, or in a direction which parallels the direction of the shaft upon which the saws are mounted, is a beam 2, which serves as a guiding support for the shifter frames. This beam 2,

I have shown as a casting which is secured 50 to a rolled channel bar 20. The beam 2 has a horizontal web 21 and a vertical web 22, the horizontal web extending from the vertical web in a direction away from the saws. The two webs are joined and the beam 55 formed thereby is placed in such position that the angle between the two webs faces away from the saws, the apex of the angle being toward the saws. Upon the lower edge of the vertical web 22, is formed a 60 trackway 23 for supporting engagement with the shifter frame. This trackway is preferably formed upon the upper surface of a small flange which projects horizontally from what may be called the inner side of 65 this web or the side which is away from the saws. This trackway thus faces upward or toward the web 21. The web 21 is provided on its under surface with two guideways which are parallel with each other and with 70 the lower guideway 23. These guideways are preferably formed as channels or grooves which are adapted to receive a guiding and bearing roller. The form of channel preferably is one which has two opposing surfaces 75 24, at opposite sides of the channel and lying in vertical planes. Centrally of these channels and projecting slightly downward is a ridge or rib 25, having a horizontal plane surface.

The shifter frame 1 differs from the shifter frame of the patent above referred to, mainly in its lower portion. The shifter frame herein shown has an upper section 10, which lies nearest to the saws, of a construction substantially the same as that of the shifter frame as shown in said patent. It, however, has a section 11, which extends downward past the guide bar 2 and a section 12 extending from the lower end of the 85 section 11, back toward the guide bar under the flange 21. The end of the section 12 has guiding support from the trackway 23. The form of this support consists preferably of a wheel or roller, 4, which is journaled 90 on the end of the section 12.

From the lower section 12 of the shifter frame, extend two arms 13 and 14, in oppo-

site directions, and also inclining upwardly, to points which bring their upper ends closely adjacent to the guide channels formed in the lower side of the web 21. Upon 5 the ends of each of these arms is journaled a guide roller 4, similar to that which is mounted directly upon the end of section 12. The pivot pins for all of these rollers preferably project slightly beyond the face of 10 the roller, this end being adapted to contact with the rib 25, so as to hold the shifter frame securely in position and prevent its rocking.

Each frame is supported from three 15 points, said points consisting of the three rollers. The two rollers carried by the arms 13 and 14, in coöperation with the end bearing of the pivot for the lower roller, prevent twisting of the frame in a horizontal 20 plane. The lower roller coöperating with the end bearings of the pivot pins for the upper rollers prevents lateral rocking upon the lower roller. A rocking of the shifter frame in the plane of the saw is prevented by the same contacts.

The triangular recess which exists above the flange 21, I prefer to cover by a thin plate 5, of sheet metal. This prevents shavings and chips accumulating in this recess. 30 As the guide bearings for the shifter frames are all under and thoroughly covered by the flange 21, there is small possibility of dust getting on these guideways and preventing smooth working of the device.

35 I claim as my invention—

1. A guide frame for saw shifter mechanisms having connected vertical and horizontal webs with the apex of the angle between them toward the saws, the vertical 40 web having one set of guiding surfaces and the horizontal web having two sets of guiding surfaces, said guiding surfaces being parallel to the plane of one or the other web and being at that side of the webs which 45 face inward of the angle between them.

2. A guide frame for saw shifter mechanisms having a vertical web and a horizontal web placed with the apex of the angle formed thereby toward the saws, the lower 50 edge of the vertical web having a rib projecting into the angle included between the webs and provided with an upwardly facing guide surface, and the lower surface of the horizontal web having two grooves therein 55 facing downward, the side surfaces of said grooves forming parallel guiding surfaces.

3. A guide frame for saw shifter mechanisms having connected vertical and horizontal webs placed with the apex of the 60 angle between them toward the saws, the inner side of the vertical web having two guiding surfaces toward its lower edge and lying, respectively, in a vertical and in a

horizontal plane, the under surface of the horizontal web having two guiding channels 65 therein, each of said channels having a central guiding surface lying in a horizontal plane and opposite edge guiding surfaces lying in parallel vertical planes.

4. In an edger guide, in combination, a 70 transversely extending beam having a horizontal web and a vertical web placed with the angle between said webs away from the saws, three guideways carried by the inner faces of said webs, a shifter frame having 75 three guides separated to coincide with the apices of a triangle and engaging each its respective guideway of said beam.

5. In an edger guide, in combination, a 80 transversely extending beam having a horizontal and a vertical web, the horizontal web having two channels in its under side having parallel sides and the vertical web having a guideway along its lower edge at the side facing toward the channel-containing 85 surface of the horizontal web, a shifter frame having an upper section extending over the top of said beam, a section extending downward past the horizontal web and a section extending under said horizontal 90 web, and arms extending oppositely from said last section and carrying wheels entering each its respective channel in the horizontal web, and a wheel journaled on the frame and engaging the guideway of the 95 vertical web.

6. In an edger guide, in combination, a transversely extending beam having an upwardly facing wheelway extending adjacent to its lower edge and a horizontally extending web located upwardly of and extending over said wheelway, said latter web having two parallel, downwardly-facing channels constituting wheel guides or trackways, a shifter frame extending over said beam 105 about and under the web and having arms with laterally separated ends, each adjacent to its respective channel in the web, wheels carried upon said arms and entering said channel, and a wheel mounted on the frame 110 and engaging the third wheelway.

7. In an edger guide, in combination, a transversely extending beam having an upwardly-facing wheelway extending adjacent to its lower edge and a horizontally extending web located upwardly of and extending over said wheelway, said web having two parallel, downwardly-facing channels constituting wheel guides or trackways, a shifter frame extending over said beam 120 about and under the web and having arms with laterally separated ends, each adjacent to its respective channel in the web, wheels carried upon said arms and entering said channel, and a wheel mounted on the frame 125 and engaging the third wheelway, each of

said wheelways having a bearing or guide surface perpendicular to the surfaces which are engaged by the wheel peripheries.

8. In an edger guide, in combination, a shifter frame carrying three triangularly separated pivot pins, a roller fitting upon each pin, a guide frame having three guide-ways receiving each its one of said rollers

and having two surfaces engaged, respectively, by the periphery of the roller and by the end surface of the pivot pin.

AUGUST BOYER.
